UNITED STATES PATENT OFFICE.

CHARLES P. DOLAN, OF BOSTON, MASSACHUSETTS.

TREMOLO-METER.

No. 878,615.

Specification of Letters Patent.

Patented Feb. 11, 1908.

Application filed June 8, 1907. Serial No. 377,915.

To all whom it may concern:

Be it known that I, CHARLES P. DOLAN, a citizen of the United States, and resident of Boston, county of Suffolk, State of Massachusetts, have invented an Improvement in Tremolo-Meters, of which the following description, in connection with the accompanying drawing, is a specification, like letters on the drawing representing like parts.

10 This invention has for its object the production of an instrument designed specifically for use in teaching piano tuning, to assist the student in learning and memorizing the different rates of speed and the graduation of the same which represent the different number 15 of vibrations of the tones essential to a third or sixth in the perfect temperament. The tremolo system of setting the temperament of a piano is also known as the "Chickering" 20 method, and is the only positive proof by means of which the tuner can be assured that the fourths and fifths are tuned properly.

If the fourths and fifths were tuned perfectly in setting a temperament the tremolo 25 system as a proof of the correctness of the work would have no value, but in order to set a perfectly uniform scale in the octave within which the temperament is laid, whether it be the octave of C or the octave of F, the fourths 30 and fifths must be "shaded" or tuned imperfectly, some being tuned a certain number of vibrations on the sharp side and some on the flat side of the smooth or perfect tone. Were 35 all of the fourths and fifths tuned perfect or smooth the last fourth or fifth to be tuned would be very rough and would contain all of the vibrations that should be distributed among the other fourths and fifths, each one containing its proper share of the vibrations 40 until the rough fourth or fifth, termed the "wolf" in the temperament, contains only its proportionate share.

When the fourths and fifths are tuned properly the intervals of the thirds and sixths will contain vibrations which will beat at a rate of speed called 45 a tremolo. When the temperament is laid between the middle octave of F and F these tremolos will graduate in speed from the third of F and A, which is the lower and 50 slowest third, to the third of C and E, which is the upper and fastest third, each succeeding third up from the third of F and A being somewhat faster.

The value of the tremolo system is manifest 55 when it is remembered that if the speed of the beat of any third is too fast or too

slow it at once indicates that the fourth or fifth governing such tremolo is too sharp or too flat.

It is known that every piano contains more 60 or less false strings or single wires containing vibrations within themselves, making it impossible to accurately count the relative number of vibrations between the fourth or fifth, and were it not for the tremolos of the 65 thirds and sixths it would be mere guess-work to attempt such counting. If, however, the tuner thoroughly understands and can recognize the rates of speed required in the tremolos of the thirds and sixths it is immaterial 70 how many false waves the fourth or fifth contains, and my present invention assists the tuner in acquiring readily and accurately the understanding of the rates of speed required in the tremolos of the thirds and 75 sixths, and imparts the ability to recognize the same.

The tremolo meter forming the subject matter of my present invention is constructed and regulated to such a point of accuracy as 80 will give to the user a correct conception of the vibrations between the intervals of the temperament from the beat of the low or slowest tremolo up to the high or fastest tremolo.

The various novel features of my invention will be fully described in the subjoined specification and particularly pointed out in the following claims.

Figure 1 is a front elevation of a tremolo 90 meter embodying one practical form of my invention; Fig. 2 is a view of the mechanism contained within the casing, the front thereof having been removed; Fig. 3 is an enlarged 95 face view of the index or dial on which the tremolos are indicated.

The apparatus is inclosed within a suitable casing a , having a front plate a' , omitted in Fig. 2, the latter having attached to it an index or dial a^x , to be referred to more particularly hereinafter, the front plate being held in place by suitable screws a^2 , Fig. 1.

Within the casing is fixedly secured the motor mechanism and the sounding instrumentality, the former being substantially a 100 clock train of usual construction and herein comprising a strong spring motor indicated at M, Fig. 1, connected by a suitable train of gears with an escapement wheel b , and a co-operating pallet or ratchet partly shown at 105 b' and mounted on a rock-shaft b^2 . The escapement wheel is very accurately cut so

that there will be no variation in its teeth, and the ratchet b' is made with care to release the escapement wheel with absolute uniformity.

5 I employ a very powerful spring in the motor M in order that the apparatus may run a sufficient length of time without causing any variation in speed due to the diminution in the motive force of the spring, the motor 10 being wound by a suitable key applied to the arbor m , the latter being accessible through the front plate a by means of the aperture a^3 , Fig. 1. Upon the escapement shaft b^2 I secure a suitable tapper or hammer 15 c , adapted to coöperate with and strike a sounding board d of metal or other suitable material, herein shown as mounted on the frame work L of the clock train in an adjustable manner by a set-screw d' . As the 20 escapement wheel b is rotated by the spring motor the ratchet b' and its supporting shaft oscillates and the tapper c will be vibrated at a rate of speed determined by the regulating or controlling means, to be described, 25 the tapper striking upon the sounding board at each vibration.

I have herein shown the speed of the escapement regulated by an adjustable pendulum, comprising a rod e fixedly secured to and 30 depending from the front end of the shaft b^2 extended forward through the frame L , and a bob or weight e' longitudinally movable upon the oscillating member or rod e . A stop collar e^x on the lower end of the latter 35 limits downward movement of the weight and prevents it from accidentally dropping off.

Manifestly the position of the weight upon the rod e determines the effective length of 40 the regulator or pendulum, the lower the weight the slower the oscillations, and vice versa, the highest number of oscillations corresponding to the dotted line position of the weight, Fig. 2, and the lowest number 45 corresponding to its full line position. As the adjustment of the weight thus determines the rate of speed of the oscillations of the pendulum and the shaft b^2 it will be obvious that the speed at which the tapper c vibrates will 50 correspond. At the right hand side of the frame L I secure a bracket f which forms a bearing for a shaft f' extended through the front plate a' of the casing a , said shaft having fixedly secured to it a disk f^2 , Fig. 2, having 55 a peripheral groove f^3 , the length of the circumference of the disk being equal to the total distance through which the weight e' can be moved longitudinally upon the pendulum rod e , so that one revolution of the disk 60 in the direction of arrow 10, Fig. 2, will move the weight from full to dotted line position.

A flexible connection f^x , such as a silk cord, is attached at one end to the weight and at the other end to the periphery of the 65 disk within the groove as at f^4 , so that by

turning the disk in the direction of arrow 10, Fig. 2, the connection f^x will be wound up in the groove, raising the weight a distance depending upon the extent of angular movement of the disk. The connection f^x leads 70 up from the weight e to and over a small grooved guide sheave f^5 rotatably mounted on the shaft b^2 , as herein shown, and thence passes to the disk f^2 , a guard f^6 attached to the frame L overhanging the connection close 75 to the disk and preventing the connection from jumping out of the disk.

The shaft f' at the exterior of the casing has secured to it a hand or pointer f^7 , Fig. 1, the hub of which is provided with an enlarged end f^8 by which the pointer and shaft can be turned conveniently to effect angular adjustment of the disk f^2 , the dial a^x being 80 concentric with the shaft. It will now be understood that by turning the pointer to any given point of the dial more or less of the connection f^x will be let off or taken up, correspondingly adjusting the weight e' and causing the pendulum and the tapper c to be vibrated at a rate of speed corresponding to 85 the point selected. The dial is graduated in a peculiar manner, the twelve indicating 90 marks from 1 to 12, Fig. 1, each denoting that if the pointer f^7 is set opposite the same the number of vibrations of the tapper will 95 correspond to the tremolo of a third or a sixth of the temperament. That is, if the pointer is set at the graduation 3 of the dial, which corresponds to a certain major sixth, and the notes G and E of the middle octave 100 are struck simultaneously the beat of their combined tones will accord with the vibrations of the tapper, provided both G and E are properly tuned. If the pointer is set at 105 1 on the dial the tapper is vibrated at the speed of the beat of the combined tones of F and G $\sharp$ if properly tuned, a minor third, and so on.

In Fig. 3, a larger view of the dial, the 110 graduations from 1 to 12 have indicated adjacent thereto the pairs of notes to be struck by the tuner when testing his work, and for a setting of the pointer to each graduation there is a corresponding variation in the speed of the vibrations of the tapper. Consequently, by moving the pointer from one to another graduation the tuner tests his 115 work and can tell at any point just where he has made an error. To prevent a continuous rotation of the disk f^2 I put a stop pin 120 Fig. 1 between the graduations 1 and 12, in the path of the pointer, and when the instrument is not in use the pointer is left at 12, and moved to graduation or rate 1 when starting. As it is neither necessary nor 125 desirable that the tapper shall sound continuously I provide a detent, herein shown as a bent arm g , pivotally mounted at g' , Fig. 2, in the front plate a' and having a rearwardly turned free end g^2 which is 130

adapted to be swung against the pendulum, to press the same against the left hand side-wall of the casing, viewing Fig. 1. A thumb-piece g^x see Fig. 1 outside the plate a' and fast on the fulcrum g' serves to turn the 5 detent against the pendulum, to stop it, or into inoperative position to release the pendulum, as in Fig. 2. The detent is shown by dotted lines in its operative position in 10 Fig. 1.

It will be understood that by arranging the mechanism so that the lowest and highest speeds of the sounding instrumentality will correspond to the speeds of the tremolos indicated at 1 and 12 respectively on the dial 15 the indices for the intermediate tremolos can be readily positioned on the dial, so that all the tuner has to do is to set the pointer to the desired indication on the dial and compare 20 the vibrations of the tapper with the beat of the corresponding notes struck on the piano.

The instrument is simple, convenient, easily operated and readily understood, and it is of the greatest assistance in training the 25 ear of the tuner in learning the art, so that he soon obtains a clear perception of the vibrations between the intervals of the temperament and can recognize them readily.

Having fully described my invention, what 30 I claim as new and desire to secure by Letters Patent is:—

1. In apparatus of the class described, a sounding board, a coöperating tapper, a spring motor operatively connected with and 35 to vibrate the tapper, a speed regulator comprising a member fixedly connected with and oscillating in unison with the tapper and a weight longitudinally adjustable on said member, and manually operated means to at 40 will change the position of the weight upon the oscillating member, to thereby increase or decrease the oscillatory speed of such member and the vibrations of the tapper.

2. In apparatus of the class described, a 45 spring-motor, an escapement therefor, a pendulum and a tapper fixedly connected with said escapement, a weight freely movable on the pendulum toward and from its fulcrum, a sounding board with which the tapper coöperates, a manually rotatable disk, and a flexible 50 connection between the weight and the periphery of the disk, whereby rotative movement of the latter in one or the other direction will raise or lower the weight and 55 vary the speed of vibration of the pendulum and tapper.

3. In apparatus of the class described, a 60 spring-motor, an escapement therefor, a pendulum and a tapper fixedly connected with said escapement, a weight freely movable on the pendulum toward and from its fulcrum, a sounding board with which the tapper coöperates, a manually rotatable disk, a flexible 65 connection between the weight and the periphery of the disk, rotation of the latter

changing the position of the weight and thereby increasing or decreasing the vibratory speed of the tapper, a pointer fixedly connected with and to turn the disk, and a fixed dial concentric with the pointer axis and having 70 thereon a scale indicating different speeds of vibration in accordance with a predetermined plan, whereby manual setting of the pointer to a given indication causes the vibration of the tapper at the speed denoted by 75 the indication.

4. In apparatus of the class described, a 80 vibrating tapper and a sounding board with which it coöperates, a spring-motor for the tapper, speed regulating means for said motor, including a pendulum having an adjustable weight, a speed-indicating dial, a manually movable pointer coöperating therewith, and means operated by setting of the pointer to adjust the position of the pendulum weight 85 and cause the tapper to be vibrated at a speed corresponding to the selected indication on the dial.

5. In apparatus of the class described, a 90 vibrating tapper and a sounding board with which it coöperates, a spring-motor for the tapper, speed regulating means for said motor, including a pendulum having an adjustable effective length, a dial indicating speed vibrations corresponding to a predetermined 95 series of tremolos, a manually movable pointer coöperating with the dial, and means operated by setting of the pointer to adjust the effective length of the pendulum and cause the beats of the tapper on the sounding 100 board to accord with the selected indication on the dial.

6. In apparatus of the class described, a 105 tapper and a sounding board with which it coöperates, mechanism to vibrate the tapper, a dial having indications thereon denoting certain speeds of vibration, and manually controlled means to cause the tapper to strike the sounding board at a rate corresponding to any selected indication on the dial, said 110 means comprising a rotatable pointer coöperating with the dial, a pendulum having a longitudinally movable weight, and a connection between the weight and the pointer, to position the weight on the pendulum in 115 accordance with angular movement of the pointer.

7. In apparatus of the class described, a 120 spring-motor, an escapement therefor, a pendulum and a tapper fixedly connected with said escapement, a weight freely movable on the pendulum toward and from its fulcrum, a sounding board with which the tapper coöperates, a peripherally grooved 125 rotatable disk, a guide-sheave concentric with the fulcrum of the pendulum, a cord passed over the sheave and secured at its ends to the weight and grooved periphery of the disk, respectively, a pointer fixedly connected with and by which the disk may be 130

rotated, to raise or lower the weight, and a dial with which the pointer coöperates, said dial having a scale of speed vibrations whereby the setting of the pointer causes the pendulum and tapper to vibrate at an indicated speed.

8. In apparatus of the class described, a spring-motor, an escapement therefor, a pendulum and a tapper fixedly connected 10 with said escapement, a weight freely movable on the pendulum toward and from its fulcrum, a sounding board with which the tapper coöperates, and means to vary the speed of vibration of the pendulum and 15 tapper, said means including a rotatable, peripherally grooved disk the length of whose circumference is equal to the total movement of the weight, a flexible connection between the latter and the grooved periphery of the 20 disk, and a pointer attached to and by which the disk is given a predetermined angular movement.

9. In apparatus of the class described, a sounder, a motor to actuate it, an index 25 graduated to indicate various rates of vibration of the sounder according to a predetermined scale, and means, including a manually positioned pointer coöperating with the index, a pendulum, and a weight movable 30 thereon by a change in position of the pointer, to cause the vibrations of the sounder to correspond to the indication at which the pointer is stopped.

10. In apparatus of the class described, a 35 vibrating tapper a motor to actuate it, a dial having indications thereon corresponding to the varying rates of speed of the tremolos, and means, including a manually-positioned pointer, a pendulum, a weight movable thereon, and a connection between the weight and 40 the pointer, to move the weight by a change in the position of the pointer, to vary the speed of vibration of the tapper to correspond with that of the tremolo indication at which the pointer is set.

11. In apparatus of the class described, a sounding board, a coöperating tapper, a spring-motor operatively connected with and to vibrate the tapper, a speed regulator comprising a member oscillating in unison with 50 the tapper and a weight longitudinally adjustable on said member, manually operated means to at will change the position of the weight upon the oscillating member, to thereby increase or decrease the oscillatory speed 55 of such member and the vibrations of the tapper, and a detent to coöperate with said member and retain the same from movement.

In testimony whereof, I have signed my name to this specification, in the presence of 60 two subscribing witnesses.
